SPEED CUP BALANCING MACHINE

Reinhold De Witt, Flint, Mich., assignor to General Motors Corporation, Detroit, Mich., a corporation of Delaware

Application November 1, 1935, Serial No. 47,754

14 Claims. (Cl. 73—51)

This invention relates to a process and a machine for balancing a freely swinging element and has been designed particularly for balancing the speed cup of a magnetic measuring instrument.

5 The object of the invention is to effect a more accurate balancing of the speed cup, to balance the cup in a way which shall be permanent, to save time in the process of balancing, and to avoid cut and try procedure.

10 A further detail, and one useful not only in this machine but elsewhere, is the provision of a novel form of oscillating bearing to reduce friction at the bearing support.

15 Other objects and advantages will be understood from the following description.

The invention is illustrated in the accompanying drawings in which:

Fig. 1 is a top plan view, partly in section, of the novel machine.

20 Fig. 2 is a long section on line 2—2 of Fig. 1.

Fig. 3 is an elevation, partly broken away, as seen substantially from the left end of Fig. 1.

Fig. 4 is a view as seen from line 4—4 of Fig. 1.

Fig. 5 is a view as seen from line 5—5 of Fig. 2.

25 Figs. 6, 7 and 8 are perspectives of details.

Figs. 9, 9a and 9b are diagrammatic views.

30 Referring by reference characters to the drawings, numeral 11 is the base of the machine. The base has an end pedestal 13 provided with a longitudinal slot 15 guided by an elongated lug 17 extending above the base and secured by fastening means 19. The pedestal is secured to the base by fastening means 21 extending through slots 23 whereby the pedestal may be longitudinally adjusted to a limited extent and secured 35 in its position of adjustment. A pivot bolt 25 is secured in the top of the pedestal and serves as the fulcrum for a bell crank lever 27. A lug 29 secured as at 31 serves as a limiting stop for the work end 33 of the lever.

40 A second pedestal is shown at 35. Its position on the base must be accurately related to the first pedestal. This is accomplished by a slot and lug expedient marked 37. This pedestal is secured by fastening means 39. Adjacent the upper end of the pedestal is a through passage to provide reciprocatory support for a shaft 41. This shaft is formed with a head 43. A link 45 connects the end of the shaft 41 and the end 45 of lever arm 33. The head 43 is formed with an opening 47 for a purpose to be explained. A stud 49 is located in a hole 51 of the pedestal 35, its head 53 being within opening 47 when the head is in abutment with the pedestal as shown.

55 Numeral 55 is used to designate a third pedestal.

It is located on the base in alignment with the other pedestals by similar positioning means marked 57. It is secured to the base by fastening means 59. Fig. 7 shows this pedestal in perspective. It is formed with an arcuate through opening 61 and a tubular opening 63 for a bearing pin 65, the latter secured by a screw 67 through an opening 69.

5 A fourth pedestal marked 71 is secured to the base by fastening means 73. Alignment is assured by a similar expedient designated by numeral 75. This pedestal has an arcuate opening 77, like 61 of pedestal 65. It has a tubular opening supporting a rotatable spindle 79. Adjacent the inner face of the pedestal the spindle is 10 of non-circular outline as shown at 81. A crank 83 having a handle 85 is carried by the part 81 of the spindle. The right end of the spindle 79 constitutes a second bearing pin 80 and is in alignment with the bearing pin 65. Two swinging members 87 and 89 have the overlapping extremities 91 and 93 of end arms 92 and 94 journaled on pin 80 and similar overlapping extremities 95 and 97 on end arms 96 and 98 are journaled on pin 65. Each swinging member in addition to its end arms journaled as shown has an intermediate arm as at 99 and 101. Each intermediate arm is apertured to receive a die 103 designed to receive a punch 105. There are two such punches carried by axial extensions 100 and 102 of arms 96 and 98. Fig. 1 illustrates the 15 construction and mounting of the punch. The arm extension is apertured and carries therein a sleeve 107 within one end of which is an inner sleeve 109 through which slides the punch spindle 20 111. Slidable in the opposite end of sleeve 107 is a stem 113 having a rounded head 115. A coil 25 spring 117 engages the arm extension and the head 115. Stem 113 at its inner end is axially bored and threaded as at 119 to receive the inner 30 end of spindle 111. The spindle has threaded thereon a nut 121 and a spring 123 engages the nut and the inner end of sleeve 109. The extensions 100 and 102 of the two swinging members move in the arcuate slot 61 as the members rock 35 on the bearing pins 65 and 80. The swinging members have other axial extensions 125 and 127 movable in the arcuate slot 77 of pedestal 71.

40 Secured by fastening means 133 to pedestal 71 is a plate 135 having a vertical slot 137 within 45 which slides a sliding member 139. Adjacent plate 135 and the vertically sliding member 139 is a cam plate 141. It is immovably connected to sliding member 139 by pins 143, so that the cam plate and sliding member 139 move to- 50 55

gether, vertically guided by the slot in end plate 135. The cam plate has a horizontal slot 145 (see Fig. 3) to receive pins 147 extending from the ends of extensions 125, 127. It will be obvious that the pins 147 may travel horizontally in the slot 145 and thus rock the swinging members when the cam plate is reciprocated. Fig. 3 shows three positions of the cam plate, an intermediate position in full lines, and extreme upper and an extreme lower position in dash lines. The changed position of the pins 147 is shown by the use of primed reference characters. It may be here explained that when the cam plate is in the uppermost position the swinging members are rotated by the pins 147 to horizontal alignment as shown by Fig. 4. As the cam plate descends the swinging members rock toward each other. When in their position of horizontal alignment, the head 115 of the punch assembly associated with extension 102 is in alignment with the hole 47 in the head 43. The purpose of this will appear hereinafter.

The cam plate is reciprocated by rotation of the crank handle 85. The structural arrangement to so operate is as follows: On the side of pedestal 71 opposite the crank 83 the stem 73 is provided with a rigid head 149. Two pins 151 and 153 project from the head 149 and enter cam slots 155 and 157 respectively. Rocking of the crank handle 85 causes the head 149 to rotate and its pin and cam relation to the cam plate 141 effects a vertical reciprocation of the latter, which reciprocation causes rotation of two swinging members by the movement of pins 147 in the horizontal slot 145. An examination of Fig. 3 will show that the pins 151 and 153 act successively in their respective slots, this being arranged to obtain an easy and gradual moving of the cam plate.

More specifically and comparing Figs. 3, 4 and 5, it will be observed that when the parts are positioned as in Fig. 4, pin 151 is in the enlarged opening at the end of slot 155 and when the crank 83 and plate 149 begin their rotation this pin moves without function until it reaches the edge of the narrow part of slot 155, a position substantially that of the full line showing of Fig. 3. In the meantime, during this idle movement of pin 151, pin 153 has been pressing against the lower edge of the narrow part of its slot 157 and therefore pushes the cam plate downwardly, thus rotating the swinging arms 87 and 89 through the instrumentality of the pins 147 engaging the walls of horizontal slot 145. During the second part of the rotation of the crank 83 the pin 151 moves in the narrow part of slot 155 pushing the plate 141 downwardly, the pin 153 then moving without function in the enlarged end of slot 157.

Between pedestals 55 and 71 is a fifth pedestal 159. It is mounted on base 11 for guided transverse adjustment as at 161. Pedestal 159 has end posts 163 and 165 to which is secured by fastening means 167 their metallic strips 169. To the upper end of each metallic strip is secured as at 171 a holder 173 as shown best by Fig. 6. The holder has transversely disposed arms 175 between which a spool 177 is held by the conical ends of pins 179 threaded into the arms. The spool is thus freely rotatable on the coned ends of the pins. A speedometer speed cup to be balanced by the operation of the machine is shown at 181 located between the intermediate arms and the end arms 96 and 98 of the swinging members. The stem of the cup marked 183

is supported on the two spools and in the axis of pin 65. In fact the end of the pin 65 is provided with a flat jewel and engages, in thrust relation, the spindle 183. It will be seen that the clockwise rotation of handle 27 as in Fig. 1 will push the head 43 toward the left. This movement is operable to push the heads 115 and thereby the punches 105 against and through the bottom of the speed cup and into the openings 163. The discs so punched out fall to a guiding plate 185 and escape through opening 187 in the base.

As will be explained below, it is necessary to reduce to the minimum the friction between the spools and the speed cup spindle so that in the event of any unequal distribution of weight the speed cup will rotate to equalize the weight on the two sides of the vertical diameter of the cup. To that end a suitable synchronous motor 189 is attached to the base 11 as at 191. It drives a shaft 193 coupled as at 195 to a shaft 197 journaled in two arms 199 and 201 extending upwardly from the fifth pedestal. This shaft 197 has secured thereto as at 203 a multiple cam 205 located between the sheet metal strips 169 and engaging abutments 207 carried thereby. In consequence, the strips 169 and the spools 177 supported thereby are constantly moved toward and from each other. In this way the vibrating support for the speed cup spindle reduces friction to a substantially irreducible minimum. The movement of the spools simultaneously toward and from each other prevents any tendency to shift the spindle and its cup axially.

To the crank 83 is secured a pointer 209 extending axially toward the speed cup.

Fig. 8 shows a U-shaped spring 209. It is secured to base 11 at 202. Its arms engage the adjacent sides of parts 125 and 127. As the swinging members 87 and 89 are folded toward each and as the pins 147 move toward each other in the slot 145, the spring arms are tensioned. The spring energy thus stored in the arms is of assistance in rotating the swinging members back to their positions of horizontal alignment.

The operation of removing material to give an accurate static balance is as follows: With the synchronous motor in operation and with the speed cup spindle supported on the vibrating spools, the cup rotates until its out of balance weight is at the bottom of the vertical axis. The crank handle 85 is then rotated to raise the cam plate to its uppermost position, the position shown by the upper dotted lines of Fig. 3. This raises the swinging members to a position of horizontal alignment as in Fig. 4. When so positioned the arm extension 102 carries the punch assembly to a position in which the head 115 registers with the opening 47. The arm 27 is now rotated clockwise (as in Fig. 1), thus advancing the head 43 to the left. Since the head 115 of the punch associated with arm extension 102 is opposite the hole 47, its punch is not operated. However, the other punch (the one carried by extension 100) is advanced by the advance of head 43 in engagement therewith and a disc is punched out on one side of the vertical axis of the bottom wall of the cup and on the horizontal axis thereof. The disc escapes out through opening 187. Fig. 9 shows the operation just described, W₂ representing the original out of balance weight and W the hole where the disc is punched out. The balance thus disturbed causes the cup to rotate and assume a new position of rest in which the point W moves up through an angle α (see 75

Fig. 9a). The crank handle 85 is then rotated until its indicating pointer is directly opposite the hole which has been made in the cup. Such turning of the crank handle has reciprocated the cam plate and turned the swinging members so that the hole 47 is no longer opposite one of the heads 115. The handle 27 is then again rotated with the result that two additional holes W₄ W₄ are punched in the cup (see Fig. 9b). This operation has produced an accurately balanced speed cup, and has done so with a minimum expenditure of time. It avoids the dust resulting from the grinding process which it is intended to replace, thus further avoiding the need of blowers and cleaners to remove the dust. It has been found convenient to slightly incline the base to maintain contact between the end of the cup spindle 183 and the thrust bearing at the end of pin 65.

In the event that after punching the first hole W the pointer cannot be made to register with the opening so punched, the cup may be turned to bring the punched hole to the upper end of the vertical diameter when a second single hole may be punched in the horizontal axis by bringing the swinging arms to horizontal alignment. The cup may then be allowed to swing to a new position of rest after which two holes are punched as before.

To make the disclosure somewhat clearer, the following mathematical deduction will show how the cam slots are made. Referring to Fig. 9 we may assume that the cup to be balanced has been supported by its spindle and that its unbalance causes it to rotate until its unbalanced weight W₂ is at the bottom of the vertical axis. The instrument is then manipulated and a hole W is punched in the horizontal axis as explained above. This step is the equivalent of adding a weight W₁ (equal to the weight of the material removed at W) on the horizontal axis on the opposite side of the vertical axis of the disc. The disc then swings until the points W₂ W W₁ assume the positions shown in Fig. 9a, the new unbalance being represented at W₃. It is possible to cut out material at W₃ to balance the disc and this process has been used. At present it is preferred to punch two equally dimensioned holes at W₄ W₄ at an angle r from the vertical as shown by Fig. 9b. The turning of the crank 83 so that the pointer is opposite the new position of W causes the cam slot to bring the punches to the correct position for punching holes W₄ to effect the balance.

As shown on Fig. 9a, let a represent the angle through which the disc rotates after punching hole W. Angle b, its complement, is the angle between the radius through W₁ and the vertical axis.

From Fig. 9a it will be seen that

$$W_1 X = W_2 Y$$

$$\text{Since } X = R \cos a \text{ and } Y = R \sin a$$

$$W_1 R \cos a = W_2 R \sin a$$

$$W_1 \cos a = W_2 \sin a$$

$$W_2 = W_1 \frac{\cos a}{\sin a}$$

Also, W₁X₁ + W₂Y₁ = W₃R, W₃ being the amount of metal to be removed at the bottom of the vertical diameter to effect a balance.

$$\text{Since } X_1 = R \sin a + Y_1 = R \cos a$$

$$W_3 = W_1 \sin a + W_2 \cos a$$

$$W_3 = W_1 (\sin a) + W_1 \frac{\cos a}{\sin a} \cos a$$

whence

$$W_3 = W_1 \left(\sin a + \frac{\cos^2 a}{\sin a} \right)$$

$$W_3 = W_1 \sin a (1 + \cot^2 a)$$

$$W_3 = W_1 \cos a = W_1 \frac{1}{\sin a} = \frac{W_1}{\sin a}$$

since angle b is the complement of angle a and since W₁ = W

$$W_3 = \frac{W}{\cos b} \quad 10$$

Therefore, if a balance were to be secured by removing material at the bottom of the vertical diameter, automatic means should be provided such that the depth of cutting will be variable and determined by the weight of the disc first punched out and the angle a through which the disc swings so that W₃ the weight removed shall equal

$$\frac{W}{\cos b} \quad 20$$

As stated above, in accordance with the present invention it is proposed not to remove an amount of material at W₃ but to punch out equal discs at W₄ W₄ as on Fig. 9b. In this case it is not the amount of cutting determined by automatic mechanism but the angular position of the holes punched. r has been used to designate the angle between the vertical axis and the radii through W₄, the size of the punch for W₄ W₄ being the same as for W.

$$\text{Then } W_3 R = 2 W_4 R \cos r \quad 25$$

$$W_3 = 2 W_4 \cos r \quad 35$$

since

$$W_3 = \frac{W}{\cos b}$$

and since W₄ = W

$$\frac{W}{\cos b} = 2 \cos r \quad 40$$

$$\frac{1}{\cos b} = 2 \cos r \quad 45$$

$$\cos r = \frac{1}{2 \cos b}$$

The cam outline whereby, when the handle is rotated to position the pointer opposite the changed position of hole W such that the punches shall assume positions to punch holes at W₄ W₄ and balance the cup is therefore formed in accordance with the formula cos

$$r = \frac{1}{2 \cos b} \quad 55$$

There are limitations to the above process of balancing dependent upon the original amount of unbalance which at times requires a slightly different set of steps. In theory from the formula given above

r becomes 0 when b is equal to 60°

when b = 60° W = W tan of 60° = 1.73W

Therefore, if the amount of unbalance is as much as 1.73 times the weight W the process fails theoretically.

The above process requires modification also because of mechanical limitations in the event that the unbalance is as much as 1.54 times the weight W. This is due to the fact that the original unbalance may be so great that the removal of weight W causes the disc to rotate so slightly that the holes to be punched overlap. Also, be-

cause of interference of the punch mechanism itself, the angle r must not be smaller than $23^\circ 21'$.

When $r=23^\circ 21'$ $b=57^\circ$

$$5. \quad \text{if } b=57^\circ \quad W_2=W \tan b \\ = 1.54W$$

Practically, therefore, the unbalance to be corrected by the method first described is limited to cases when W_2 is not more than 1.54 times the weight W . By the modified process used when W_2 is greater than 1.54 W after punching out W and finding that W_2 is greater than W 1.54 the weight W_2 is in effect reduced by an amount W . This is done, as explained above, by rotating the disc to bring W_2 to the horizontal, and then punching a second time, whereby a new reduced unbalance ($W_2-W=W_5$) results. The amount of unbalance capable of correction by this modified process is 2.54 W since the unbalance capable of correction is W (an unbalance caused by punching W at W_2 moved to the horizontal axis) and the former maximum W 1.54 which together equal 2.54 W .

25. By this simple process, therefore, an unbalanced speed cup or any similarly fully rotating element may be quickly and accurately balanced. It requires no cut and try methods and the correction is of a permanent character.

30. In some of the following claims the angle between the vertical axis and the radius through the hole W in its position of rest is designated by b and the angle between the vertical axis and the radii through holes W_4 is designated by r .

35. I claim:

1. The process of giving static balance to an unbalanced element consisting in mounting said element for free rotation to localize its unbalanced weight in its vertical axis, removing material from one side of said axis, permitting the element to swing to a new position of rest and removing material to balance the element, the region of removal being determined by the mass of material first removed and the extent of rotation resulting from such first removal.

2. The process of balancing an out of balance freely rotatable element comprising removing material from a position in its horizontal axis at one side of its vertical axis, permitting said element to rotate after said removal of material and subsequently removing material partly from each side of its vertical axis, said positions of subsequent removal being determined by the mass of material first removed and by the rotation of the element after said removal.

3. The process of giving a static balance to an out of balance element consisting in mounting the element for free rotation whereby its out of balance weight lies in the vertical axis, removing a predetermined mass of material from one point in the horizontal axis, permitting the element to rotate through an angle to a new position of rest and subsequently removing material at two positions, the radii through said positions forming equal angles with the vertical axis and said positions being determined by the mass of material first removed and by the angle of rotation subsequent thereto.

4. The process of giving an unbalanced element a static balance consisting in mounting the element for free rotation whereby its out of balance weight lies in the vertical axis, removing material from a horizontal axis, permitting the element to rotate to a new position of rest, removing material from two positions one on each side

of the vertical axis at radial distances equal to the radial distance of the first removal of material and on radial lines making equal angles with the vertical axis, said positions determined by the mass of material first removed and by the resulting angle of rotation of the element.

5. The invention defined by claim 4 wherein the location of the positions for second removal of material is determined by the formula

$$10. \quad \cos r = \frac{1}{2 \cos b}$$

where b equals the complement of the angle through which the element rotates and r the last mentioned angle with the vertical axis.

15. 6. The process of giving static balance to an unbalanced element comprising mounting the element for free rotation, removing material at a point in its horizontal axis, rotating said element to bring said point to the uppermost point of the vertical axis, again removing material from the horizontal axis at the same radial distance, permitting the element to rotate to a new position of rest, and subsequently removing material at two positions, one on either side of the vertical axis, the radial lines of said positions making equal angles with the vertical axis and the radial distance of each being the same as the radial distance of said point.

20. 7. The process of effecting a static balance in a freely rotatable element consisting in permitting the element to rotate to a position of rest, punching a hole in the horizontal axis, permitting the element to rotate to a second position of rest and punching two holes one on each side of the vertical diameter, the location of said last-named holes being determined by the formula

$$25. \quad \cos r = \frac{1}{2 \cos b}$$

40. 8. In a machine to give static balance to an unbalanced element, means to support said element for free rotation, means to punch holes in said element simultaneously on both sides of its vertical axis, and means whereby one of said punch means becomes inoperative in a predetermined position of said punch means.

45. 9. The invention defined by claim 8, said first named supporting means comprising a plurality of supporting members and mechanism to move said members simultaneously toward and from each other.

50. 10. In a machine to give static balance to an out of balance element, means to support said element for free rotation, swinging members, punches carried thereby adapted to punch holes in said element, mechanism to rotate said swinging members to locate said punches in predetermined positions, said punches being reciprocable and having heads, and axially movable means to engage said heads and reciprocate said punches.

55. 11. The invention defined by claim 10, said movable means having an opening therein whereby in one of said predetermined positions one of said punches is not reciprocated by the movement of said movable means.

60. 12. The invention defined by claim 10, said mechanism comprising a rotatable plate provided with pins, a reciprocable plate having cam slots receiving said pins, said reciprocable plate also having a horizontal slot, said swinging members having pins received within said horizontal slot.

65. 13. In a machine to give static balance to an out of balance element, means to support said

element for free rotation, swinging members, punches carried thereby adapted to punch holes in said element, mechanism to rotate said swinging members to locate said punches in predetermined 5 positions, said punches being reciprocable and having heads, axially movable means to engage said heads and reciprocate said punches, said movable means having an opening therein whereby in one of said predetermined positions one of 10 said punches is not reciprocated by the movement of said movable means, in consequence whereof said element swings to a new position of rest after one hole has been punched therein and is thereafter balanced by rocking said swinging members to new positions of adjustment and 15 punching two holes therein.

14. In a machine to give static balance to an out of balance element, means to support said ele-

ment for free rotation, swinging members, punches carried thereby adapted to punch holes in said element, mechanism to rotate said swinging members to locate said punches in predetermined positions, said punches being reciprocable and having 5 heads, axially movable means to engage said heads and reciprocate said punches, said movable means having an opening therein whereby in one of said predetermined positions one of 10 said punches is not reciprocated by the movement of said movable means, in consequence whereof said element swings to a new position of rest after one hole only has been punched therein, said mechanism operable in response to the mass of 15 material removed and the angle of rotation of the element to locate the swinging members and the punches in position to balance the element.

REINHOLD DE WITT.
